UNITED STATES PATENT OFFICE

GERALD R. STARK, OF SOUND BEACH, CONNECTICUT, ASSIGNOR TO THE PATENT AND LICENSING CORPORATION, OF BOSTON, MASSACHUSETTS, A CORPORATION OF MASSACHUSETTS

DESIGN FOR A ROLL ROOFING

Application filed June 13, 1930. Serial No. 36,039. Term of patent 14 years.

To all whom it may concern:

Be it known that I, GERALD R. STARK, a citizen of the United States, residing at Sound Beach, in the county of Fairfield and State of Connecticut, have invented a new, original, and ornamental Design for a Roll Roofing, of which the following is a specification, reference being had to the accompanying drawing, forming part thereof.

Fig. 1 represents a plan view of a portion of an asphaltic composition roll roofing, embodying my new design.

Fig. 2 is an edge view thereof.

I claim:

The ornamental design for a roll roofing, substantially as shown.

GERALD R. STARK.
